(57) **CLAIM**
The ornamental design for a ceiling fan housing, as shown and described.**DESCRIPTION**

FIG. 1 is a lower front side perspective view of a second embodiment design of the ceiling fan motor housing with blades.

FIG. 2 is an upper front side perspective view of a second embodiment design of FIG. 1.

FIG. 3 is a front side view of the second embodiment design of FIG. 1.

FIG. 4 is a rear side view of the second embodiment design of FIG. 1.

FIG. 5 is a right side view of the second embodiment design of FIG. 1.

FIG. 6 is a left side view of the second embodiment design of FIG. 1.

FIG. 7 is a top view of the second embodiment design of FIG. 1; and,

FIG. 8 is a bottom view of the second embodiment design of FIG. 1.

The broken line showing of the canopy, support rod, blade end fasteners and motor vent openings is included for the purpose of illustrating environmental structure and forms no part of the claimed design.

1 Claim, 8 Drawing Sheets# US D635,236 S
